WINDING APPARATUS

Cyril M. Croft and Alvin W. Bergeron, Cumberland, and Frederick G. Dodge, La Vale, Md., assignors to Celanese Corporation of America, a corporation of Delaware

Application July 12, 1941, Serial No. 402,092

10 Claims. (Cl. 242—76)

This invention relates to textile apparatus and relates more particularly to a means for winding or batching fabrics on a take-up roll or shell.

When textiles are being processed after weaving and are being dyed or given some other finishing treatment as on a jig or a winch, the fabrics are normally taken-up or wound on rolls or shells. In this form, the fabrics are easily handled and the compact character of the roll of fabric facilitates the movement of the fabric from one finishing process to another. One serious difficulty, however, has been encountered in winding or batching fabrics of certain weaves. This difficulty resides in the fact that such fabrics tend to pile up or build up to a sharp point along the selvedge. Frequently the selvedge builds up to such an extent that it turns or falls over causing an excessive amount of creasing in the fabric. In addition, the excessive build up of the selvedge causes a certain amount of stretching along the selvedge which makes the fabric more difficult to handle in finishing operations due to slack selvedges.

It is, therefore, an important object of our invention to provide means in a device for winding fabrics whereby the fabrics may be wound so as to avoid the piling up of the fabric selvedges.

Another object of our invention is the provision of apparatus for winding fabrics which is simple in operation and durable in construction.

Other objects of our invention together with certain details of construction and combination of parts will be more particularly described in the specification and pointed out in the appended claims.

In the drawing:

Figure 1 is a side elevational view showing the path of the moving fabric, the rolls over which it passes, and the roll upon which it is batched or wound.

Figure 2 is a view, partly in cross-section, taken along the line 2—2 in Figure 1 in the direction of the arrows; and

Figure 3 is a side-elevational view analogous to the view in Figure 1 and showing, in addition, the means whereby each of the rolls is driven.

Like reference numerals indicate like parts throughout the several views of the drawing.

Referring now to the drawing, and particularly to Figure 1 there is shown a fabric winding device in which a fabric 4, which is to be wound, is passed in the direction indicated by the arrows over a driven guide-roll 5, over a pair of guide-rolls 6 and 7, over a driven guide-roll 8, and is then taken up on a roll or winding shell 9 mounted on

5 a shaft 10, thus forming roll of fabric 11. Roll 8 is symmetrically mounted on a shaft 12, while rolls 6 and 7 are symmetrically mounted on shafts 13 and 14, respectively, and all three rolls rotate in fixed rotational paths. Roll 5, however, is so mounted as to describe an unsymmetrical or eccentric path as shown in Figure 1. To this end, roll 5 has fixed in the center of one end thereof a stub shaft 15, and at the other end thereof roll 5 is provided with a stub shaft 16 which shaft is so mounted as to be slightly off-center. Shafts 15 and 16 rotate in suitable bearings 17 which bearings are mounted in brackets 18 as by knuckles 19, said brackets being supported by channels 20 which constitute a portion of the frame (not shown) of the winding device. By reason of the mounting of bearings 17 in knuckle joints 19, free relative movement between said bearings and brackets 18 may be obtained 20 thus permitting the unhampered, eccentric, off-center rotation of roll 5.

Roll 8 and roll 5 are driven by the rotation of shaft 10, the latter being driven by suitable means (not shown) while rolls 6 and 7 act merely as 25 guide-rolls and are undriven. To drive roll 5 and roll 8, shaft 10, as shown in Figure 3, is provided with a grooved pulley 21 fixed thereto. Roll 8 is provided with a grooved pulley 22 mounted on the shaft 12 of said roll and roll 5 is provided with a 30 grooved pulley 23 mounted on the shaft 16 of said roll. In addition to pulley 22, shaft 12 has mounted thereon a smaller grooved pulley 24. The rotation of shaft 10 rotates pulley 21 which in turn drives pulley 22 by means of a belt 25. Pulley 24 35 on shaft 12 is likewise rotated and this movement is transmitted to pulley 23 through a belt 26, thus causing roll 5 to rotate.

Due to the fact that the diameter of pulley 21 is 40 smaller than that of pulley 22, as shown in Figure 3, roll 8 rotates at a somewhat lower speed than roll 9, and, since pulley 24 is of a smaller diameter than pulley 23, roll 5 is rotated at an even lower speed than roll 8. The result of the 45 progressive increase in speed of the rolls 5, 8 and 9 is that fabric 4, which is being wound or batched on roll 8 at a constant speed, is caused to slide over the surface of roll 5 as roll 5 rotates, since the fabric is moving at a speed greater than the surface or periphery of said roll 5. This sliding 50 action likewise occurs when fabric 4 passes over roll 8. Since roll 5 is describing an eccentric rotational motion, the fabric 4, sliding across the surface thereof, is given a side to side movement as it moves over roll 5. This side to side motion 55 of the fabric causes said fabric to wind on roll

9 with the selvedges out of register or staggered. Since the position of the selvedge is thus staggered as the fabric is wound, the piling up of the selvedges is overcome and, as a result, turned and stretched selvedges are avoided as is excessive creasing of the fabric.

While we have shown the use of belt and pulley means whereby roll 5 and roll 8 may be driven, it will be appreciated that these rolls may likewise be driven by gear mechanism or by means of a chain and sprocket drive. Also, said rolls may be driven from a source of power independent of that employed for rotating roll 9. While we preferably cause only roll 5 to describe the eccentric rotational motion which imparts the desired side to side motion to the moving fabric, roll 8 may likewise be constructed in a manner analogous to roll 5. In this way both rolls may be caused to describe an eccentric motion, either in unison or somewhat out of register, so as to impart a side to side motion of any extent in the fabric being wound.

It is to be understood that the foregoing detailed description and drawing are given merely by way of illustration and that many variations may be made therein without departing from the spirit of our invention.

Having described our invention, what we desire to secure by Letters Patent is:

1. In a device for winding fabrics wherein a fabric passes over a plurality of driven guide-rolls to be taken up on a take-up roll, the combination with a driven take-up roll of means adapted to cause one end of at least one of said driven guide-rolls to rotate eccentrically with respect to the other end.

2. In a device for winding fabrics wherein a fabric passes over a plurality of driven guide-rolls to be taken up on a take-up roll, the combination with a driven take-up roll of means adapted to drive at least some of said driven guide-rolls, and means adapted to cause one end of at least one of said driven guide-rolls to rotate eccentrically with respect to the other end.

3. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls and means adapted to cause one end of at least one of said driven guide-rolls to rotate eccentrically with respect to the other end.

4. In a device for winding fabrics wherein a fabric passes over a plurality of driven guide-rolls to be taken up on a take-up roll, the combination with a driven take-up roll of means cooperating with said driven take-up roll to drive at least some of said guide-rolls, said cooperating means being adapted to drive said driven guide-rolls at a peripheral speed below that of said driven take-up roll, and means adapted to cause one end of at least one of said driven guide-rolls to rotate eccentrically with respect to the other end.

5. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls, said cooperating means including a belt and pulley drive adapted to drive said driven guide-rolls at a peripheral speed below that of said driven take-up roll.

up roll, and means adapted to cause one end of at least one of said driven guide-rolls to rotate eccentrically with respect to the other end.

6. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls, said cooperating means including a belt and pulley drive adapted to drive said driven guide-rolls at a peripheral speed below that of said driven take-up roll, and means adapted to cause one end of one of said driven guide rolls to rotate eccentrically with respect to the other end.

7. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls, said cooperating means including a belt and pulley drive adapted to drive said driven guide-rolls at a peripheral speed below that of said driven take-up roll, and means adapted to cause one end of one of said driven guide-rolls to rotate eccentrically with respect to the other end, said eccentrically-rotating, driven, guide-roll being driven at a speed below that of the other driven guide-rolls.

8. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls, said cooperating means including a belt and pulley drive adapted to drive said driven guide-rolls at a peripheral speed below that of said driven take-up roll, and means including an off-center shaft adapted to cause one end of at least one of said driven guide-rolls to rotate eccentrically with respect to the other end.

9. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls, said cooperating means including a belt and pulley drive adapted to drive said driven guide-rolls at a peripheral speed below that of said driven take-up roll, and means including an off-center shaft adapted to cause one end of said driven rolls to rotate eccentrically with respect to the other end.

10. In a device for winding fabrics wherein a fabric passes over a plurality of driven guide-rolls to be taken up on a take-up roll, the combination with a driven take-up roll of means cooperating with said driven take-up roll to drive at least some of said driven guide-rolls, said cooperating means including a belt and pulley drive adapted to drive said driven guide-rolls at a peripheral speed below that of said driven take-up roll, and means including an off-center shaft adapted to cause one end of said driven rolls to rotate eccentrically with respect to the other end, said eccentrically-rotating, driven, guide-roll being driven at a speed below that of the other driven guide-rolls.
